(57) **CLAIM**

The ornamental design for a feedstock measurement device, as shown and described.

DESCRIPTION

FIG. 1 is top, front and right side perspective of a feedstock measurement device, in this view with a pivot arm extended; FIG. 2 is a side view, seen from a left side, of the feedstock measurement device shown in FIG. 1, in this view with the pivot arm retracted;

FIG. 3 is a rear view of the feedstock measurement device of FIG. 1, in this view with the pivot arm retracted;

FIG. 4 is a front view of the feedstock measurement device of FIG. 1, with the pivot arm in an extended position;

FIG. 5 is a perspective view, from a left underside, of the feedstock measurement device of FIG. 1, in this view with the pivot arm retracted;

FIG. 6 depicts an isometric view of the feedstock measurement tool of FIG. 1 supported on a tool disclosed in broken lines to illustrate a use environment;

FIG. 7 depicts the feedstock measurement device of FIG. 1 and FIG. 6 shown in condition of use with a feedstock disclosed in broken line, in this view with the pivot arm retracted; and,

FIG. 8 depicts the feedstock measurement device of FIG. 1 and FIG. 6 shown in condition of use with the feedstock disclosed in broken line, in the view with the pivot arm extended and biased against a feedstock.

The characteristic feature of the design resides in the overall appearance of the feedstock measurement device.

Broken lines in FIG. 6 depict a tool on which the feedstock measurement device is supported in use. The tool is not part of the subject design.

Additional broken lines in FIGS. 7-8 depict a feedstock that is being measured by the feedstock measurement device in use. The feedstock is not part of the subject design.
